UNITED STATES PATENT OFFICE.

GEORGE G. GREENBURG, OF CHICAGO, ILLINOIS.

DESIGN FOR A BADGE.

SPECIFICATION forming part of Design No. 36,341, dated June 2, 1903.

Application filed May 6, 1903. Serial No. 155,946. Term of patent 3½ years.

To all whom it may concern:

Be it known that I, GEORGE G. GREENBURG, residing at Chicago, in the county of Cook and State of Illinois, have invented a new, original, and ornamental Design for Badges, of which the following is a specification, reference being had to the accompanying drawing, forming part thereof.

The drawing shows a front view of the new design.

Having thus described my invention, what I claim as new, and desire to secure by Letters Patent, is—

The ornamental design for a badge as shown

GEORGE G. GREENBURG.
